UNITED STATES PATENT OFFICE

121,469

DESIGN FOR A COMBINED SHOE SOLE AND HEEL

Jules Fern, Oscar Fern, and Harry Sobel,
Los Angeles, Calif.

Application April 26, 1940, Serial No. 91,974

Term of patent 7 years

To all whom it may concern:

Be it known that we, Jules Fern, Oscar Fern, and Harry Sobel, all citizens of the United States, residing at Los Angeles, in the county of Los Angeles and State of California, have invented a new, original, and ornamental Design for a Combined Shoe Sole and Heel, of which the following is a specification, reference being had to the accompanying drawing, forming part thereof.

Fig. 1 is a rear perspective view of a combined shoe sole and heel, showing our new design;

Fig. 2 is a front perspective view; and
Fig. 3 is a side elevational view of the same.

We claim:

The ornamental design for a combined shoe sole and heel, as shown.

JULES FERN.
OSCAR FERN.
HARRY SOBEL.
